DESIGN FOR A HANDBAG

Irving Pichel, New York, N. Y.

Application June 27, 1945, Serial No. 120,370

Term of patent 7 years

(Cl. D87—2)

To all whom it may concern:

Be it known that I, Irving Pichel, a citizen of the United States of America, residing in New York, county of New York, and State of New York, have invented a new, original, and ornamental Design for a Handbag, of which the following is a specification, reference being had to the accompanying drawing, forming part thereof.

Fig. 1 is a front perspective view of a handbag showing my new design.

Fig. 2 is a fragmentary rear perspective view thereof; part of the bag being broken away for convenience of illustration, and

Fig. 3 is a top plan view of the frame portions shown in Figs. 1 and 2.

The dominant feature of my design resides in the portions shown in solid lines.

I claim:

The ornamental design for a handbag, substantially as shown and described.

IRVING PICHEL.
